CLAIM

The ornamental design for a laptop holder, as shown and described.

DESCRIPTION

FIG. 1 is a top perspective view of the laptop holder;
FIG. 2 is a bottom perspective view of the laptop holder;
FIG. 3 is a front view of the laptop holder;
FIG. 4 is a back view of the laptop holder;
FIG. 5 is a right side view of the laptop holder;
FIG. 6 is a top view of the laptop holder; and,
FIG. 7 is a bottom view of the laptop holder.
The broken lines depict portions of the laptop holder which form no part of the claimed design. The left side view of the laptop holder (not shown) is a mirror image of the right side view shown in FIG. 5.

1 Claim, 7 Drawing Sheets
